UNITED STATES PATENT OFFICE.

WILLIAM S. SMITH AND SAMUEL N. CRIDER, OF HAGERSTOWN, MARYLAND.

DRIVE-BELT.

1,313,028.

Specification of Letters Patent.

Patented Aug. 12, 1919.

Application filed September 19, 1918. Serial No. 254,709.

To all whom it may concern:

Be it known that we, WILLIAM S. SMITH and SAMUEL N. CRIDER, citizens of the United States, residing at Hagerstown, in 5 the county of Washington and State of Maryland, have invented certain new and useful Improvements in Drive-Belts, of which the following is a specification.

This invention relates to drive belts of 10 the detachable built up link type and is primarily intended for driving the cooling fans provided on automobile engines, having especially in mind such use in connection with Ford engines. However, it is capable 15 of use with equally good results wherever a belt of this nature can be employed.

Its objects are to provide such a belt which can be built up from links and easily adjusted as to length by the addition or removal of links; which can be easily repaired 20 simply by the removal of a worn link or links and the substitution therefor of new links; to provide for great strength and durability in such belts; to provide a belt of 25 this nature which will not stretch appreciably in use and become loose; and to protect the pulleys of the engine from wear of metallic parts while at the same time preventing undesirable noise in operation, all 30 of which objects are accomplished by the construction, combination and arrangement of parts, all as hereinafter more particularly set forth, described and claimed.

In the accompanying drawings:

35 Figure 1 represents a side elevation of a belt embodying our invention as applied in use;

Fig. 2, a detail enlarged view of several of the links, several of said links being 40 shown in longitudinal plane section;

Fig. 3, a similar view in side elevation, several of the links being shown in longitudinal cross section; and

Fig. 4, a transverse cross-section through 45 one of the links.

Referring now in detail to the drawings, A represents the drive pulley mounted on the shaft E and which drives belt D, which passes over the pulley B connected to the hub of fan C mounted on a suitable shaft or post, all as is usual.

The belt D is composed of a number of links, each of which consists of a piece of sheet metal 1, which may easily be, and preferably is, formed by stamping out from a sheet of metal. This metal piece 1 is pro-

vided with a long transverse slot 2 near one end and a narrow strap which is bent over to form a hook 3 at the other end, the width of the hook being slightly less than the 60 length of slot 2.

Also, said sheet metal part or core 1 is provided at its central portion with a perforation 6.

A rivet is passed through this perforation 65 until its large head 5 is in engagement with the inner side of the plate 1, when the leather, or other suitable, covering 4 is wrapped around plate 1 over rivet head 5 and has its end portions overlap each other 70 on the outside of the link, when the bifurcations 7 of the rivet are to be spread and hammered down, as shown in Fig. 3, this hammering down or riveting over of the ends 7 resulting in bending the plate 1, giving 75 it a slight curve on the inner side of the belt, as shown in Fig. 3, so that it will conform to the curved surface of the pulleys much better than a straight plate would.

Normally, before assembly into a belt, the 80 individual links have their hooks 3 left open, as shown in Fig. 3. To build up a belt the hook 3, in this condition, is passed through the slot 2 of the adjacent link and then bent down, as shown in Fig. 2, and so on, until 85 the belt is complete, when it is to be slipped on the pulleys A and B with the ends 7 of the rivets on the outside of the belt and the heads 5 presented inward, this arrangement of the links avoiding wear by metallic parts 90 on the pulleys A and B, avoiding unpleasant noise that would be caused by the ends 7 clicking against the pulleys A and B, were said ends 7 presented inward, and also putting the strains on the hooks 3 at a point 95 where it will have the least effect or tendency to pull said hooks 3 open. The curve in the plates 1 also has a value in this connection as it avoids sharp angles at the points of connection of the links.

Having thus described our invention, what we claim as new and desire to secure by Letters Patent is:

1. A belt link comprising a core of strong material having an opening near one end and provided with a hook on its other end portion, said hook being of relatively flexible material and adapted to be passed through an opening in a similar link core and closed thereafter, a suitable frictional 105 covering and a fastening device passing through said core, having one end covered 110

by said covering and the other end flush with the surface of said covering, whereby said device is protected and said covering is secured to said core.

- 5 2. A belt consisting of a series of detachable links, each link comprising a sheet metal core having one end portion slotted and the other end portion formed into a hook passed through the slot of the adjacent link and 10 bent over to close it against the escape thereof, a rivet for securing a suitable covering to said core, and a covering wrapped around said core, covering the head of said rivet, and held in wrapped position by spreading 15 the exposed end of the rivet.
3. A belt consisting of a series of detachable links, each link comprising a sheet metal core having one end portion slotted and the

other end portion formed into a hook passed through the slot of the adjacent link and 20 bent over to close it against the escape thereof, a covering wrapped around said core, and a rivet having its head located between said covering and said core, passing through said core and said covering and having its 25 exposed end spread to hold said covering to said core.

In testimony whereof, we have signed our names to this specification in the presence of two subscribing witnesses.

WILLIAM S. SMITH.
SAMUEL N. CRIDER.
